REFRIGERATING APPARATUS

Ralph W. Doeg, Detroit, Mich., assignor to Nash-Kelvinator Corporation, Detroit, Mich., a corporation of Maryland

Application April 24, 1939, Serial No. 269,598

9 Claims. (Cl. 230—58)

This invention relates to refrigerating apparatus and more particularly to compressors employed in such apparatus.

It is an object of the present invention to provide an improved system for unloading a refrigerant compressor which enables initiation of compressor operation under no working load conditions and to operate for a period of time before assuming the working load and to provide improved means for sealing certain unloading mechanism to avoid noises and to provide proper sealing surfaces in the unloading system.

Another object is to provide an improved system of lubricating and sealing unloading mechanism of a refrigerant compressor.

Another object of the invention is to provide an improved motor compressor unit of the hermetically sealed type wherein the motor and compressor is assembled as a unitary structure and,

Further objects and advantages of the present invention will be apparent from the following description, reference being had to the accompanying drawings.

25 In the drawings:

Fig. 1 is a side elevational view of the motor-compressor schematically illustrated with a refrigerating system;

30 Fig. 2 is a longitudinal cross sectional view of the invention;

Fig. 3 is a cross sectional view taken substantially on line 3—3 of Fig. 2;

35 Fig. 4 is a cross sectional view taken substantially on line 4—4 of Fig. 2;

Fig. 5 is a cross sectional view taken substantially on line 5—5 of Fig. 2;

Fig. 6 is a cross sectional view taken substantially on line 6—6 of Fig. 4;

40 Fig. 7 is a cross sectional view taken substantially on line 7—7 of Fig. 6;

Fig. 8 is a cross sectional view taken substantially on line 8—8 of Fig. 4;

45 Fig. 9 is a vertical cross sectional view of an unloading device used in the invention;

Fig. 10 is a longitudinal cross sectional view of a modified form of the invention;

Fig. 11 is a cross sectional view taken substantially on line 11—11 of Fig. 10;

50 Fig. 12 is a longitudinal cross sectional view of another modified form of the invention;

Fig. 13 is a cross sectional view taken substantially on line 13—13 of Fig. 12;

55 Fig. 14 is a vertical cross sectional view of a modified form of unloading device;

Fig. 15 is a longitudinal cross sectional view of a further modified form of the invention;

Fig. 16 is a cross sectional view taken substantially on line 16—16 of Fig. 12, with parts broken away and parts shown in section;

Fig. 17 is a longitudinal cross sectional view of a still further modified form of the invention;

Fig. 18 is a cross sectional view taken substantially on line 18—18 of Fig. 17, with parts broken away and parts shown in section.

Referring to the drawings, 20 designates a sealed casing for a motor-compressor unit of a refrigerant system. The gaseous refrigerant is drawn from the evaporator 23 through a conduit 24 to the casing 20 where it is compressed and delivered by a conduit 25 to a condenser 21 and the liquid refrigerant is then conducted to a high side float 22, and then to the evaporator 23. The operation of the motor-compressor unit is controlled by a thermostatically operated switch (not shown) connected to and responsive to the change of temperature of the evaporator 23.

The motor-compressor casing 20 is divided by an integral partition 32 and a removable partition 39 into a motor compartment 26, a compressor compartment 27 and a high pressure compartment 28. The casing 20 is sealed by end walls 30 and 31. The partition 32 is provided with a bearing 33, and a bearing 38 is provided in the removable partition 39 in which a shaft 35 is journaled. The partition 39 is removably secured to the casing by bolts 40. A rotor 44 of an electric motor is affixed to the reduced portion 42 of the shaft 35 that extends into compartment 26, and a stator 45 is securely fixed to the casing 20 and in alignment with the rotor. A lock nut 47 is screwed onto the shaft 42 and engages an end of the rotor and forces the rotor against a collar 48, which bears against a shoulder 49 on the shaft 35 for locking the rotor to the shaft.

A hollow bolt 53 has screw-threaded engagement with an end of the shaft 35, and a nut 51 carried by the bolt and engaging an end of the bearing 38 cooperates with the collar 48 in limiting any longitudinal movement of the shaft 35 in its bearings.

Within the compartment 27, a cylinder 61 is formed in the wall of the casing 20, and partition 32. The cylinder bore extends through the casing 20, and is provided with a valve plate 63 and a cylinder head 64 mounted on the outer wall of the casing. A piston 60 is mounted for reciprocation in the cylinder and has a connecting rod 59 pivoted thereto, and which is connected to an eccentric 58 on the shaft 35.

A coupling 69 connects the suction line or conduit 24 with a passage 67 formed in the wall of the casing 20 and compartment 27. A filter 68 is attached to the coupling for filtering the gaseous refrigerant discharged into passage 67. Passage 67 communicates with a passage 70 extending from the motor compartment 26 and a spring controlled valve 72 is interposed between these passages for preventing any backflow of oil and refrigerant to the evaporator. The refrigerant is drawn from compartment 26, see Fig. 8, through a filter 75 in a passage 76 located in the partition 32 and is delivered to the intake chamber 77, in the cylinder head 64, see Fig. 7, 15 where a reed valve 79 controls the delivery of refrigerant to the cylinder 61. A valve 82 of the cylinder head controls communication between exhaust port 81 on the valve plate and chamber 84, and from which chamber 84 the refrigerant is delivered into passages 85 and 86 formed in partition 39 and conducted to a chamber 87 formed in a housing 90 of the compartment 28. The housing 90 is secured to the bearing 38 by bolts 91 and encloses the end of the shaft 35. A 20 tube 92 delivers the refrigerant from chamber 87 to the high pressure compartment 28 where it passes through the outlet 118 to the condenser. A shield 93 having a central opening 94 therein is located within the housing 90 and is held 30 in place by clamping the turned down edges 95 thereof between the bearing 38 and the housing 90 for forming an auxiliary chamber 89 around the bolt 53 and shaft 35. The bolt 53 has a passage 96 formed therein which communicates with a passage 98 extending throughout the length of the shaft 35. By providing the shield 93 the agitation of the separated oil in the housing 90 by the rotation of the bolt 53 is reduced to a minimum and thus the oil will flow through opening 40 94 in the shield and into the passages 96 and 98 without producing foam.

In the starting of the compressor, when powered by a motor of the low starting torque, the compressor should be required to do as little work as possible, and thus there should be a balance of pressures on both sides of the piston until the motor has gained sufficient speed to operate the piston as a pump. To accomplish this there is provided an unloader valve 100 which consists of a housing 101 having a sliding weight 102. A needle valve 103 is attached to said weight by pin 104 and located in a passage 105. A seat 106 is arranged to cooperate with the needle valve 103. A spring 108 seated on the bottom of housing 101 presses against a shoulder 107 of the weight 102 and urges said weight toward a plug 109 of the housing. Slots 110, see Fig. 2, are provided in the weight 102 to permit with passage 105 the further flow of refrigerant into the compartment 26 when the needle valve 103 is unseated, and also to prevent any dashpot action when the needle valve is seated and the housing is filled with oil.

In the drawing the needle valve is seated, thus closing the valve, which will be the position taken by the valve when the motor has gained sufficient momentum so that by centrifugal force the weight will move outwardly against the compression of the spring 108. During the idle period or at the start of the cycle the spring 108 will force the weight 102 toward the plug 109 thus unseating the valve 103 and permitting a free flow of gaseous refrigerant or an equalization of pressures between the compartments 26 and 28 by way of passages 96 and 98. However upon

the seating of valve 103 communication between the compartments will be broken and thus there will be a withdrawal of evaporated refrigerant from the evaporator 23 through the conduit 24, passages 67 and 70 into the compartment 26. 5 From the compartment 26 the refrigerant and any oil absorbed thereby will be drawn by suction through passage 76, which passage is located adjacent the bottom of compartment 26, into the intake chamber 77 past reed valve 79 10 into the cylinder 61. The piston will force the compressed refrigerant under pressure past the valve 82 into the chamber 84 through the passages 85 and 86 into the chamber 87. Upon reaching this chamber 87 the oil and refrigerant 15 will separate due to the change of velocity in passing from a small orifice 86 into an enlarged chamber 87, and the refrigerant will pass through the tube 92 into the compartment 28 from which it will eventually flow through the outlet 118 to 20 the condenser 21. The oil upon being separated will be collected in the bottom of chamber 87 until there is a sufficient quantity to overflow through opening 94 to enter the passages 96 and 98 to furnish a supply of oil to aid in sealing the 25 unloading valve 100 against gas leakage between the compartments during the operation of the compressor.

In order to provide for a quiet and efficient operation and the lubrication of shaft 35 in 30 bearing 38 a passage 112 is formed in the wall 39 which passage communicates, through a screen 111 with the high pressure compartment 28 within which a quantity of oil is maintained. The compressed refrigerant supplied to compartment 28 will exert a pressure on the body of oil causing it to be forced up the passage 112 to the shaft. As the bearing 38 opens into the high pressure chamber 87 and the lower pressure compartment 27 the oil will work towards the compartment 27 and thereby provide for a quiet bearing as well as reducing wear to a minimum and this oil will further aid in sealing against gas leakage along the bearing.

A predetermined amount of oil is maintained 45 in compartment 27 to lubricate the frictional surfaces of the connecting rod, piston and eccentric. These parts when in motion will splash the oil upwardly, to be caught in trough 115 mounted 50 on partition 32, and delivered from said trough to lubricate shaft 35 and bearing 33 by means of passageway 117.

In Figs. 10 and 11 there is shown a modified form of the invention in which the mechanism of motor, compressor and unloader are assembled together as a unit and slid into the casing 150 and sealed by an end plate 151 that is welded, soldered, press fitted or the like. The mechanism is assembled on a casting 152 which includes a motor support section 153, a compressor 60 housing 154 and a bearing section 155. Shaft 157 is journalled in the bore 156 formed in the bearing section 155, and it is also journalled in a bearing 158 formed in a plate 159, which plate serves as part of the compressor housing 154 to form 65 the compression chamber 160. The casting 152 is so arranged within the casing 150 as to provide therewith a high pressure compartment 162 and a low pressure compartment 161; said last named compartment having the shaft 157 extending therein and a rotor 163 operatively connected thereto. A stator 164 is fixedly secured to section 153 of casting 152 in compartment 161 and cooperates with the rotor. An eccentric 182 is formed integral with the shaft 157 upon which 70

there is connected a connecting rod 165 which reciprocates a piston 166 in a cylinder 167, which cylinder is formed in the casting 152. The cylinder is provided with a valve plate 168, an inlet reed valve 169, an exhaust valve 170, an exhaust port 175 formed in the cylinder head 171.

The evaporated gaseous refrigerant is admitted into the motor compartment 161 from the conduit 24 through the inlet port 172 where it is drawn through conduit 173 into passage 174 formed in the partition wall past the reed valve 169 into the cylinder 167, where it is compressed and discharged through valve 170 and port 175, into the cylinder head 171. A passage 176 formed in the cylinder wall conducts the compressed refrigerant to a chamber 177 of a housing 96, and similar to chamber 87, shown in Fig. 2. The refrigerant is discharged from chamber 177 through tube 178 into the high pressure compartment 162.

A passage 98 for unloading the compressor during the starting period extends from chamber 177 through shaft 157 to an unloader valve 179 affixed to the end of shaft 157 in the motor compartment 161. This unloader valve and the operation thereof are the same as shown in Figs. 2 and 9.

Lubrication of the bore 156 is provided through a passage 180 formed in the housing 184 that opens below the oil level 181 in the compartment 162. The oil will be forced up the passage to lubricate the shaft 157 in the bore 156 by the compressed refrigerant of the compartment. The oil of the compartment also acts as a cooling agent for the compressor which is partially surrounded thereby. Upon the rotation of the eccentric 182 in the compartment 160 oil will be splashed therein some of which will be caught in the pocket 183 formed in the plate 169 from which it will be delivered by a passage 184 to the bearing 158.

In the modification shown in Fig. 12 the motor, compressor and unloader device are all assembled as a unit upon a casting 210 which is slid into a shell 212 that is hermetically sealed by an end plate 213 by welding, soldering or the like. A central wall or partition 215 formed integrally with the casting 210 serves to divide the shell into a low pressure compartment 217 and a high pressure compartment 218. Formed centrally of the wall 215 is a bearing 219 for journaling a shaft 221. A rotor 223 of an electric motor is fixed to the reduced portion 222 of the shaft 221 and a stator 225 is fixedly secured to the casting to function with the rotor. Formed on the shaft 221 within the low pressure compartment 217 is a crank 226 and journalled to said crank is a connecting rod 228, to which a piston 229 is joined by wrist pin 230. The piston reciprocates within a cylinder 232 formed integrally with the casting 215, and a compression chamber is formed between the piston and a valve supporting plate 236. A cylinder head 237 is mounted on the open end of cylinder 232.

Refrigerant gas is delivered to the compartment 217 by conduit 24, through an inlet coupling 271 and conduit 272. A valve 273 in conduit 272 prevents any back flow through the conduit. A tube 238 extends above oil level of compartment 217 and conducts the refrigerant to intake chamber 240. A reed valve 242 controls the flow of refrigerant gases from chamber 240 into the cylinder 232 for compression, while the discharge valve 245 controls the flow of compressed gases from the cylinder. A passage 246

formed in the wall of the casting 210, which supports the stator 225, communicates with the cylinder head 237 for conducting the compressed refrigerant therefrom. A conduit 247 is connected to the casting 210 and communicates with 5 passage 246 for conducting the refrigerant to the compartment 218.

The shaft 221 is provided with an axial passage 98 which provides communication between the compartments 217 and 218, as previously described. The unloader valve 100, in this instance is provided with a chamber 248 formed in a wall thereof, which has communication with the needle valve 103 by a duct 250. An opening 249 is formed in the wall of the unloader through which the tube or conduit 247 extends for discharging the compressed refrigerant and oil into the chamber 248, where the oil may be separated from the refrigerant and the refrigerant allowed to escape into the compartment 218, and conducted through the outlet 251 in the casing to a condenser.

Whenever the oil level 243 in compartment 217 rises above the tube 238, oil will be drawn in with the refrigerant and discharged from tube 251 into chamber 249 where due to the change of velocity the oil particles will separate and flow into passage 250 while the refrigerant gases will pass through opening 249 into the high pressure compartment 218. The oil will be stored in passage 250 where it is held by centrifugal force to seal the valve of the unloader mechanism against the flow of refrigerant during the operation of the compressor.

Peripheral grooves 260 formed on the shaft 221 for lubricating purposes are supplied with oil by a tube 270 connected to bearing 219 and extending below the oil level 262 in the compartment 218. An annular groove 261 is formed on the shaft 221 and communicates with an axial passage 263 formed in the shaft 221. A passage 265 formed in the connecting rod 228 has communication with passage 263 for conducting lubricant to the crank, connecting rod and wrist pin.

Figs. 15 and 16 are similar to the other structures including a reciprocating compressor 316 mounted on a casting 314 which has a sliding fit within the casing 350. The casting supports a stator winding 320 of an electric motor, within 50 which is a rotor 351. The rotor 351 drives the compressor through a shaft 310 journalled in a bearing 312 of the casting. The casting divides the casing into a low pressure compartment 318 in which the compressor is located, and a high pressure compartment 322. An unloading valve 324 is connected to the shaft within the compartment 318 and has communication with an axial passage 326 in the shaft 310. A tube 328 through which the compressed refrigerant is discharged 60 from the compressor 316 extends into the high pressure compartment 322 and conforms somewhat to the circular contour of the casing, and terminates in a downwardly extending portion for discharging the refrigerant and oil into a 65 reservoir 335 formed on the upper surface of the bearing 312. The tube is preferably enlarged or has a greater diameter as at 330 throughout a portion of its length, which allows for expansion of the refrigerant. The tube is 70 provided with perforations or openings 334 for admitting lubricant or oil, located in the compartment at 331, thereto, and which is carried by the compressed refrigerant to the reservoir. Evaporated gaseous refrigerant will be admit- 75

ted to the compressor through inlet connection 327 into compartment 318 where the refrigerant with some particles of oil will be drawn through the tube 340 into the compressor 416 by the action of the piston. The compressed gases will be discharged through tube 328 into enlarged tube 330 and will be delivered to reservoir 335 along with the particles of oil that have entered the tube 330 through the openings 334. Upon reaching the reservoir the oil and gas will separate due to the change of velocity and the oil will drop to the bottom of the reservoir 335 where it will flow through passage 337 to the peripheral groove 339 where it will provide lubrication for the shaft and bearing 312 and then into the passage 326 to the unloader 324, for forming a seal therefor. Thus the oil will provide for quiet and efficient lubrication and operation and will also serve as a seal for preventing gas leakage. During the unloading of the compressor, the refrigerant in compartment 322 will flow together with the oil in the reservoir 335 through the passages 337 and 326, and to the unloader valve 324 and into compartment 318 for balancing the pressure in the compartments.

An oil passage 342 formed in the bearing 312 and web of the casting 314 forms a communication between the oil reservoir 331 and the grooves 343 formed on shaft 310. Due to the pressure in compartment 322 oil will be forced through passage 342 to the grooves 343 from whence it will tend to work towards the low pressure compartment 318 thus eventually flowing into passage 344 which passage will deliver the oil to the compressor for lubricating purposes.

The modified forms shown in Figs. 17 and 18 are similar to the other structures including a reciprocating compressor 416 mounted on a casting 414 which has a sliding fit within the casting 150. The casting supports a stator winding 420 of an electric motor, within which is a rotor 451. The rotor 451 drives the compressor through a shaft 410 journalled in a bearing 412 of the casting. The casting divides the casing into a high pressure compartment 422 and a low pressure compartment 418 in which the compressor 416 is located. The compressor head 446 and part of the compressor 416 are submerged below the oil level 445 maintained in the compartment for cooling purposes. An unloading valve 424 is connected to the shaft within the compartment 418 and has communication with an axial passage 426, in the shaft 410. A tube 428 through which the compressed refrigerant is discharged from the compressor head 446 extends into the high pressure compartment 422 and conforms somewhat to the circular contour of the casing, and terminates in a downwardly extending portion for discharging the refrigerant and oil into a reservoir 435 formed on the upper surface of the bearing 412. The tube is preferably enlarged or has a greater diameter as at 430 throughout a greater portion of its length, which allows for expansion of the refrigerant. The tube is provided with perforations or openings 434 for admitting lubricant or oil, located in the compartment at 431, thereto, and which is carried by the compressed refrigerant to the reservoir.

Evaporated gaseous refrigerant will be admitted to the compressor through inlet connection 427 into compartment 418 where the refrigerant with some particles of oil will be drawn through the tube 440 into the compressor 416 by the action of the piston. The compressed gases will be delivered to the compressor head

446 and then discharged through tube 428 into enlarged tube 430 and will be delivered to the reservoir 435 along with the particles of oil that have entered the tube 430 through the openings 434. Upon reaching the reservoir the oil and gas will separate due to the change of velocity and the oil will drop to the bottom of the reservoir 435 when it will flow through passage 437 to the peripheral groove 439 where it will provide lubrication for the shaft and bearing 412 and then into the passage 426 to the unloader 424 for forming a seal therefor. Thus the oil will provide for quiet and efficient lubrication and operation and will also serve as a seal for preventing gas leakage. During the unloading of the compressor, the refrigerant in compartment 422 will flow together with the oil in the reservoir 435 through the passages 437 and 426 to the unloader valve 424 and into compartment 418 for balancing the pressures in the compartments.

An oil tube 442 extends from below the oil level 431 of compartment 422 through bearing 412 to the peripheral grooves 443 formed on shaft 410. Due to the pressure in compartment 422 oil will be forced through tube 442 to the grooves 443 from whence it will tend to work towards the low pressure compartment 418 thus eventually flowing into passage 444 which passage will deliver the oil to the compressor for lubricating purposes.

Although only a preferred form of the invention has been illustrated, and that form described in detail, it will be apparent to those skilled in the art that various modifications may be made therein without departing from the spirit of the invention or from the scope of the appended claims.

I claim:

1. A refrigerating apparatus comprising a casing having a partition for dividing the casing into a high pressure compartment and a low pressure compartment, a shaft journalled in said partition, a motor and a compressor in said casing and connected to said shaft whereby the compressor is operated upon the rotation of the motor, means for conducting high pressure refrigerant from said compressor to the high pressure compartment, an oil reservoir in said high pressure compartment, means forming communication with said oil reservoir and shaft whereby the oil of the reservoir may be supplied to the shaft by the pressure of the refrigerant in said high pressure compartment.

2. In a refrigerating apparatus, comprising a casing having a high pressure, a low pressure and a compressor compartment, a motor mounted in said low pressure compartment, a compressor mounted in said compressor compartment, partitions in said casing between said casing between said compartments, shaft bearings formed in said partitions, a shaft mounted in said bearings connected to said motor and compressor and extending into said high pressure compartment, a housing in said high pressure compartment enclosing an end of said shaft, a centrifugal unloader valve mounted on the opposite end of said shaft and located in said low pressure compartment, said shaft having a passage therethrough forming a communication between the high and low pressure compartments during the idle and starting periods of the motor-compressor for equalizing the pressure of said compartments, means for conducting low pressure refrigerant from the low pressure compartment to said compartment.

pressor, means for conducting the compressed refrigerant from said compressor to said housing where any oil in said refrigerant may separate therefrom, means for conducting the separated refrigerant from said housing to the high pressure compartment.

3. In a refrigerating apparatus, comprising a casing having a high pressure, a low pressure and a compressor compartment, a motor mounted in said low pressure compartment, a compressor mounted in said compressor compartment, partitions in said casing between said compartments, shaft bearings formed in said partitions, a shaft mounted in said bearings connected to said motor and compressor and extending into said high pressure compartment, a housing in said high pressure compartment enclosing an end of said shaft, a centrifugal unloader valve mounted on the opposite end of said shaft and located in said low pressure compartment, said shaft having a passage therethrough forming a communication between the high and low pressure compartments during the idle and starting periods of the motor-compressor for equalizing the pressure of said compartments, means for conducting low pressure refrigerant from the low pressure compartment to said compressor, means for conducting the compressed refrigerant from said compressor to said housing where any oil in said refrigerant may separate therefrom, means for conducting the separated refrigerant from said housing to the high pressure compartment, said passage in said shaft conducting oil to said unloader valve from said housing for sealing the valve when closed and cutting off communication between the compartments, said high pressure compartment having an oil sump therein, means forming a passage from said sump to said shaft bearings through which oil is delivered under the pressure of the refrigerant in said high pressure compartment.

4. In a refrigerating apparatus comprising a casing having high and low pressure compartments, a motor mounted in said low pressure compartment, a compressor including a cylinder and a piston mounted in said casing, a partition in said casing between said compartments, a shaft bearing formed in said partition, a shaft journalled in said bearing and connecting said motor and compressor, a housing in said high pressure compartment having communication therewith for the flow of refrigerant to said compartment, a centrifugal unloader valve mounted on an end of said shaft, said shaft having a passage therethrough forming a communication between the compartments and auxiliary chamber during the idle and starting periods of the motor-compressor for equalizing the pressure of said compartments, means for conducting low pressure refrigerant from the low pressure compartment to the compressor, means for conducting the compressed refrigerant from said compressor to said housing where any oil in said refrigerant may be separated therefrom, said passage in said shaft conducting oil to said unloader valve from said housing for sealing the valve when closed and cutting off communication between the compartments, said high pressure compartment having an oil sump therein, means forming a passage from said sump to said shaft bearings through which oil is delivered under the pressure of the refrigerant in said high pressure compartment.

5. In a refrigerating apparatus comprising a casing having high and low pressure compart-

ments, a motor mounted in said high pressure compartment, a compressor composed of a cylinder, cylinder head and piston mounted in said low pressure compartment, said cylinder head and part of the cylinder submerged in the oil in said low pressure compartment for cooling, a partition in said casing between said compartments, a shaft bearing formed in said partition, a shaft journalled in said bearing and connecting said motor and compressor, said shaft having a passage therethrough forming a communication between the compartments during the idle and starting periods of the motor-compressor for equalizing the pressure of said compartments, a centrifugal unloader valve mounted on an end of said shaft, an auxiliary chamber having communication with said unloader, means for conducting low pressure refrigerant from the low pressure compartment to the compressor, means for conducting the compressed refrigerant from said compressor to said auxiliary chamber where any oil in said refrigerant may be separated therefrom, means for conducting the separated refrigerant from said chamber to the high pressure compartment.

6. A refrigerating apparatus comprising a casing having a high pressure compartment and a low pressure compartment, an electric motor mounted in one of the compartments and a compressor in the other compartment, said high pressure compartment having a body of oil therein, a partition in said casing between said compartments, a shaft journalled in said partition and connected to the motor and compressor whereby the compressor is operated upon the rotation of the motor, means for conducting high pressure refrigerant from the compressor to the high pressure compartment, means for conducting oil from the high pressure compartment to the shaft, said oil being elevated through said means by the pressure of the refrigerant thereupon.

7. A refrigerating apparatus comprising a casing having a partition therein dividing the casing into a high pressure compartment and a low pressure compartment, a motor mounted in one compartment and a compressor mounted in the other compartment, a shaft journalled in said partition and connecting the motor and compressor, said high pressure compartment having a body of oil therein, an oil separating chamber carried by said partition, a conduit extending from said compressor through said body of oil in the high pressure compartment and discharging into said oil separating chamber, said conduit provided with orifices for the admission of oil to said conduit whereby oil will be elevated to said separating chamber by the high pressure refrigerant discharged through said conduit.

8. In a refrigerating apparatus comprising a casing having a partition dividing the casing into motor and compressor compartments, a motor mounted in said motor compartment, a compressor mounted in said compressor compartment, a shaft bearing formed in said partition, a shaft journalled in said bearing and connected to said motor and compressor, a centrifugal unloader valve mounted on the end of said shaft in said motor compartment and having a chamber formed therewith, said shaft having a passage therethrough forming a communication between the compartments during the idle and starting periods of the motor-compressor for equalizing the pressure of said compartments, means for conducting low pressure refrigerant

to the compressor, means for conducting the compressed refrigerant from said compressor to said chamber where any oil in said refrigerant may be separated therefrom, said oil flowing from said chamber by means of a passage to said valve for sealing the valve against gas leakage between the compartments.

9. In a refrigerating apparatus comprising a casing adapted to contain lubricant, a motor and a compressor positioned in the casing, a support-

ing member for both the motor and the compressor and being arranged in engagement with the casing and partially submerged in the lubricant and being arranged to support said motor so that a portion of the windings thereof is submerged in lubricant and cylinder walls of the compressor are submerged in the lubricant for cooling the motor and compressor. 5
